UNITED STATES PATENT OFFICE.

ROY C. TOWNSEND, OF BELOIT, WISCONSIN.

GAS TRACTION-ENGINE.

1,172,075.

Specification of Letters Patent. Patented Feb. 15, 1916.

Application filed March 30, 1911. Serial No. 617,840.

To all whom it may concern:

Be it known that I, Roy C. Townsend, a citizen of the United States, residing at Beloit, in the county of Rock and State 5 of Wisconsin, have invented certain new and useful Improvements in Gas Traction-Engines; and I do hereby declare the following to be a full, clear, and exact description of the invention, such as will enable 10 others skilled in the art to which it appertains to make and use the same.

This invention relates to new and useful improvements in gas traction engines, and more particularly to that class consisting of 15 a combination supporting frame and cooling device for the engine.

An object of this invention is to improve and simplify devices of this character, rendering them comparatively simple and inexpensive to manufacture, reliable and efficient in use, and readily operated.

With the above and other objects in view, this invention resides in the novel features of construction, formations, combinations 25 and arrangements of parts to be hereinafter more fully described, claimed and illustrated in the accompanying drawing, in which—

Figure 1 is a side elevation of my invention; and Fig. 2 is a longitudinal sectional 30 view thereof.

Referring to the drawings by characters of reference, the numeral 1 designates generally a traction engine, consisting of a compartment 2, containing a part of the 35 transmission gearing (not shown) to the front of which is secured a cylindrical casing 3, closed at its opposite ends by heads 4 and 5. The engine 1 is mounted upon suitable wheels 6 and 7, the former of which 40 are driven through the medium of suitable gearing from a gas engine 8, mounted upon the cab 2 adjacent the cylindrical casing 3.

The engine 8 is incased by the usual cooling jacket 9, from the upper and lower 45 sides of which lead pipes or conduits 10 and 11. The former of the conduits leads to a suitable dome 12 secured to the outer side of the casing 3, the purpose of which dome 12 is to provide an elevated reservoir to 50 accommodate a quantity of water, the minimum level of which is to be kept on the same plane, or possibly above that of the

top of the water jacket 9, whereby the latter is kept flooded at all times, while the latter of the said conduits is connected with 55 the lower side of the casing 3 adjacent the head 4.

A suitable casing, forming a compartment 13, is bolted, or otherwise secured, to the forward end of the casing 3, and is connected to the forward end of the gear containing housing by means of suitable tubes 14, which extend through the heads 4 and 5. A stack 15 is secured to the upper end of the compartment 13, while the exhaust pipe 60 of the engine is extended into said compartment through one side thereof, and directed upward in the direction of the said stack 15. This exhaust serves to create a draft through the tubes 14, which obviously 65 cools the water or the like contained within the cylindrical casing 3.

A suitable pump 11^a is connected to the conduit 11 for the purpose of circulating the water through the before mentioned 70 jacket 9.

From the foregoing disclosure, taken in connection with the accompanying drawings, it will be manifest that a combination 80 frame and cooling device of the nature described is provided for which will fulfil all of the necessary requirements of such a device.

The previous disclosures illustrated one embodiment of my invention, but it is to be 85 understood that minor changes in the details of construction may be resorted to within the scope of the appended claim without departing from the spirit of the invention.

Having thus fully described this invention, what I claim as new and desire to secure by Letters Patent is:

A traction engine comprising a cylindrical casing having an enlarged portion at 95 one end and an inclosed compartment at the other end, heads fitted in said casing, a plurality of air draft tubes supported by said heads and extending through said casing and communicating with the inclosed 100 compartment, an engine mounted on said casing and provided with a water jacket, a water dome on said casing communicating with the water in said casing, a water pipe

extending from the top of the water jacket to the top of said dome, a water pipe leading from the bottom of said water jacket to the bottom of said cylindrical casing, an exhaust pipe leading from said engine to said inclosed compartment, a smoke stack on said compartment, said exhaust pipe leading into said smoke stack, and means

for circulating the water from said casing through said water jacket.

In testimony whereof I affix my signature in presence of two witnesses.

ROY C. TOWNSEND.
